UNITED STATES PATENT OFFICE.

CARRIE E. HAYES, OF CHARLESTON, WEST VIRGINIA.

CORSET.

1,126,207.

Specification of Letters Patent.

Patented Jan. 26, 1915.

Application filed November 29, 1913. Serial No. 803,696.

To all whom it may concern:

Be it known that I, CARRIE E. HAYES, a citizen of the United States, residing at Charleston, in the county of Kanawha and 5 State of West Virginia, have invented certain new and useful Improvements in Corsets, of which the following is a specification.

My invention relates to improvements in 10 corsets, the primary object being to provide a generally improved corset or brace adapted to give the correct poise by bringing and maintaining the various parts of the body in proper position.

15 The improved corset or brace is particularly designed and adapted to pull up or support the abdomen and press in between the shoulder blades bringing back the shoulders and at the same time leaving the dia- 20 phram and lungs free as well as preventing any injury to the stomach, liver, heart, and other vital organs.

The improved brace is adapted to inforce 25 deep breathing by forcing the chest up whereby every cell of the lungs is brought into use, and by causing a proper poise or carriage to be maintained greatly strengthens the external and internal muscles.

While the present embodiment of the in- 30 vention is in the form for use by young ladies in physical culture classes or to be worn by women in lieu of the ordinary corset, it is apparent that the same may be readily adapted for use by men and children 35 as a combined abdominal and shoulder brace without the usual discomforts of the braces now in common use.

With the above mentioned and other ends in view, the invention consists in the novel 40 construction, arrangement, and combination of parts, hereinafter described, illustrated in one of its embodiments in the accompanying drawings, and particularly pointed out in the appended claims.

45 Referring to the drawings, forming a part of this specification, Figure 1, is a side elevation of the improved corset-brace as it appears applied to the body for use. Fig. 2, an enlarged front elevation of the same de- 50 tached. Fig. 3, a rear elevation of the same, Fig. 4, a front elevation showing a modified form of the upper front portion of the im- proved corset-brace.

Similar numerals of reference designate

like parts throughout all the figures of the 55 drawings.

The improved corset-brace comprises a suitable fabric body made up of reinforced side sections 1, adapted to conform to the contour of the body at the waist and hip por- 60 tions thereof, said side sections terminating in tapered leg and hose extension portions 1^a, and being provided at their top with bust supporting members 2, the latter being sepa- 65 rate from the side sections 1, and abdominal supporting sections 3, by means of a trans- versely extending crescent shaped opening or recess 4, the adjacent inner or free ends of the bust-supporting members 2, being preferably connected to the sections 1, and 70 3, through the medium of the metallic lac- ing strips 5, formed along the marginal edges of the sections 1, and 3, the ends of said lacing strips being extended forming bridging members 5^a, bridging the space 75 across the crescent shaped opening or re- cess 4, as shown most clearly in Fig. 2, of the drawings. The lacing strips 5, may be provided with the usual lacing eyelets 6, and lacings 7, the abdominal supporting sec- 80 tion 3, tapering or converging from top to bottom and preferably comprising two parts divided along a central or median line and reinforced by means of reinforcing metallic sheets or strips 8, the upper and lower por- 85 tions of the two-part abdominal supporting section 3, being detachably secured in any suitable and convenient manner, in the pres- ent instance, by means of lacings 9, but pref- erably by means of hooks and eyes or other 90 suitable attaching devices.

The bust supporting members 2, are connected by means of an elastic strap 10, said bust supporting members being connected to the rear top portions of the side sections 1, 95 by means of shoulder straps 11.

The side sections 1, are adapted to be se- 100 cured at the rear by means of a lacing 12, passing through suitable eyelets in lacing strips 13, and as a means for holding the im- proved brace down and in proper position the rear portions of the leg and hose exten- 105 sion portions 1^a, are connected by means of an elastic strap 14, connecting the same to- gether, and adapted to pass beneath the seat of the wearer, as illustrated in Fig. 1, of the drawings.

The tapered extension portions 1^a, are pro-

vided with hose supporter straps 15, one branch 15^a, being adapted to be secured near the front portion of the stocking, as illustrated in Fig. 1, the other branch 15^b, being adapted to be secured to the stocking or hose at the side portion thereof as shown.

10 The side sections 1, may be suitably reinforced, as for example,—by means of the vertically extending curved ribs or bone members 16, and the bust supporting members 2, may likewise be reinforced, as for example, by means of diagonally disposed ribs or reinforcing members 17.

15 In Fig. 4, of the accompanying drawings, I have shown a modified form of the upper front portion of the improved corset brace in which the transversely extending crescent shaped opening or recess 4, is dispensed with, the bust supporting members 2, being independent of the abdominal supporting section 3, and being connected at their front by the lacing string or cord 18; and the upper rear portions of the side sections 1, are connected to the shoulder straps 11, by 25 means of a connecting cord 19.

20 From the foregoing description, taken in connection with the accompanying drawings, the construction and advantages of my invention will be readily understood.

25 Having thus described an embodiment of

my invention, what I claim and desire to secure by Letters Patent is,—

1. In a corset brace, side and abdominal sections connected to each other, the top portion of each side section being provided with a transverse opening defining bust supporting members extending from the under arm portions of said side sections, and lacing strips extending from the adjacent marginal edges of said side and abdominal sections 40 and across said transverse openings and connected to said bust supporting members.

2. In a corset brace, side sections laced together along a median line at the back and connected in front by means of a downwardly tapering abdominal supporting section, said side sections being provided with transverse recesses defining a transverse crescent shaped opening above said abdominal supporting section and terminating near 50 the under arm portions of said side sections, and bridging members extending from said abdominal and side sections and secured to said bust supporting members.

55 In testimony whereof I have affixed my signature in presence of two witnesses.

CARRIE E. HAYES.
